SHIFT CONTAINER VENDING MECHANISM

Robert Z. Greene, Glen Ridge, and Christianz
Gabrielson, Belleville, N. J., assignors to Rowe
Manufacturing Co., Inc., New York, N. Y., a cor-
poration of New York

Application September 23, 1938, Serial No. 231,290

6 Claims. (Cl. 312—67)

This invention relates to vending machines, and more particularly to means for containing supplies of articles to be vended in such machines.

It is an object of the invention to provide, in the class of vending machine in which several different kinds of brands of merchandise are vended, means for varying the ratios between the numbers of the various kinds or brands of merchandise carried by providing reserve storage spaces for certain brands, and preferably utilizing portions of the containers for certain brands as storage spaces for others.

In the cigarette vending field, which may be taken as typical, machines are customarily provided with a number of vertical chutes or hoppers adapted to hold columns of packages of cigarettes, the usual number of such hoppers being six or eight. As will be apparent, the variation in the numbers of different brands of cigarettes which the machine can hold is severely limited. For example, in a six column machine, if five brands are to be vended, the only possibility is to carry an equal number of four brands and twice as many of a fifth. It is, however, desirable to approximate the number of packages of various brands stocked in the machine to proportionality to the sales volume of the various brands. In accordance with the present invention in its preferred form, one or more of the hoppers may be divided into two sections, one of which may contain a short column of a slow moving brand and the other of which may contain a short column of a popular brand and is adapted to replenish the supply of that brand in an adjacent hopper. As will be apparent, if but one hopper in a six-hopper machine is so adapted by dividing it into two sections of equal capacity, it becomes possible to load the machine with equal numbers of four brands, half as many of a fifth, and one and one-half times as many of a sixth. Where five brands are stocked it is possible to carry, for example, equal numbers of three brands, half as many of a fourth, and two and one-half times as many of a fifth, and still other variations will be readily apparent. Where more than one hopper in a machine is so adapted the possibility of variation is even more increased.

A further object of the invention is to adapt certain of the hoppers in a machine to carrying either a single column in the manner well known in the art or a divided column in accordance with the present invention, which still further increases the possibility of variation in the ratios

between the numbers of various brands carried.

A still further object of the invention is to carry out the foregoing objects in a simple and rugged construction and to adapt the normal delivery mechanism of the machine to carrying out the desired shifts from one container to another in a reliable and fool-proof manner.

With the foregoing and other objects, which will appear in the following full description, in mind, the invention consists in the combinations, arrangements and details of parts which will first be described in connection with the accompanying drawings and then more particularly pointed out in the appended claims.

In the drawings—

Figure 1 is a front elevation of a container unit for a cigarette vending machine embodying the invention in a preferred form;

Figure 2 is a vertical section taken on the line 2—2 of Figure 1 and on an enlarged scale;

Figure 3 is a rear elevation of the lower part of the device of Figure 1, and on an enlarged scale;

Figure 4 is a section on the line 4—4 of Figure 2 and on the same scale as Figure 3; and

Figure 5 is an enlarged sectional detail taken on the line 5—5 of Figure 4.

Referring to these figures generally, the device illustrated comprises a container unit generally of a type familiar in the art and such as is shown, for example, in co-pending Rowe and Gabrielson application No. 26,734. The coin control mechanism and cabinet to be employed form no part of the present invention and may be of any usual or suitable type. Accordingly, these features are not illustrated or described.

Referring particularly to Figure 1, the container unit illustrated comprises six vertical chutes or hoppers numbered from 1 to 6, of which numbers 3 and 5 are adapted to split column operation in the manner to be described. As will be apparent from the following full description, it is possible with the mechanism disclosed, to adapt as many as half of the hoppers in a machine of this type to such operation.

As shown, the hoppers comprise side walls 7 and back walls 8 and are welded or otherwise fastened together to form a row of adjacent hoppers reinforced by cross bar 9 at the front and plate 10 at the rear, and forming a unitary structure adapted to be inserted in or removed from a vending machine as a whole. These hoppers are of generally conventional shape and are open at the front save for flanges 11, and are open at the top for loading and adapted to hold

vertical columns of cigarette packages 12. The bottoms of all hoppers are similar and are open, the columns of cigarettes therein being supported by members 13 carried on delivery plungers 14, which are movably borne in grooves, not shown, in a bed plate 15. Cigarettes are delivered in the usual manner by pulling a plunger 14 out as far as it will go (to the left in Figure 2), which removes the support 13 from the column of cigarettes, which thereupon descends by gravity 10 until the lowermost package is resting on the bed plate 15. Upon return of the plunger to the position of Figure 2, the lowermost package is expelled for delivery and the column and plunger are again in the condition of Figure 2 except 15 that there is one less package of cigarettes in the container.

Mounted on the rear of each of the hoppers 1 to 6 is a match hopper 16 adapted to contain a vertical column of books or packages of matches 17. Each column of matches is supported by the upper end of a bell crank lever 18, which is pivoted at 19 to a bracket 20 on the plate 10 and biased rearwardly to the position of Figure 2 by a spring 21. Formed on one arm of bell crank lever 18 is a stop 22 which prevents rearward motion beyond the position of Figure 2 and the other arm of the lever 18 is pivotally connected at 23 to a link 24, the other end of which is in turn pivotally connected at 25 to a second bell 30 crank 26 pivotally mounted at 27 in bracket 28 upon the rear wall of the cigarette hopper. The lower arm of bell crank 26 forms a shoe positioned in the path of a package of cigarettes during ejection by the plunger 14 of that cigarette chute. Through the mechanism just described a package of cigarettes during ejection will rotate bell crank 18 forwardly (counter-clockwise in Figure 2), removing the support 30 from the column of match books 17 which thereupon descends and rests upon flanges 29 at the bottom of hopper 16. When the package of cigarettes has passed bell crank 26, spring 21 returns bell crank 18 to the position of Figure 2, ejecting the lowermost match book 17 for delivery to the customer.

As shown in Figure 1, the upper portions 3' and 5' of hoppers 3 and 5 are adapted to rotate clockwise or to the left, being formed separately from the lower portions and supported pivotally by a pair of pins 30, one of which is affixed to the rear wall of the container unit and the other of which is carried by an upright 31, fastened to cross bar 9. These upper portions 3' and 5' are advantageously strengthened by cross braces 32 and each carries a pair of studs 33 and 34 adapted to ride in arcuate slots 35 and 36, respectively, formed in the rear wall of the unit. The lower portions 3' and 5' of the hoppers 3 and 5 are adapted for loading either from the top or from the front, flanges 11 being cut away, as shown in Figure 1, to permit the latter, and have at their upper ends shelves or supports 37 which are clipped onto walls 7 at their upper ends, as shown in Figure 1, and may be removed if desired. These shelves 37 serve to support columns of cigarettes in containers 3' and 5' when the latter are in the position of container 3' in Figure 1.

As shown in Figure 1, the column of cigarettes contained in hopper 2 has been depleted to a point where its top is just below shelf 37 in the adjoining hopper 3 and mechanism is about to be operated when another package is delivered from the hopper 2 to cause the swingable hopper

3' to move over to a position similar to that of hopper 5', and in which position the column of cigarettes therein will no longer be supported by shelf 37 and will descend into hopper 2 for delivery therefrom. As also shown in Figure 1, this action has already taken place in hopper 4 which is being supplied with cigarettes from the swingable hopper 5'.

This shifting action is controlled through mechanism to be described, by a toe 38, pivotally mounted at 39 in brackets 40 attached to the rear wall of the unit, and adapted to extend through a slot 41 into the cigarette containing chute or hopper (2 or 4) which is to be furnished with an additional supply of packages when partially depleted.

Each of the swingable upper hoppers 3' and 5' is biased to the left by a spring 42, one end of which is affixed to the body of the unit, as at 43, and the other is attached through a piece 44 to the upper stud 33, previously referred to. These hoppers, however, are normally prevented from swinging over by a stop 45 positioned in front of the other, or lower, stud 34. Stop 45 is formed on an arm 46 pivoted on shaft 47 carried in brackets 48 on the rear wall of the casing and normally held in the position of Figure 4 where the stop 45 prevents movement of stud 34. When, however, the column of cigarettes in a hopper to be replenished is depleted to the point indicated in column 2 of Figure 1, toe 38 is free to move into this hopper through opening 41 and the next operation of the delivery mechanism for this hopper releases hopper 3' in the following manner: As shown in Figures 3 and 4, a cross bar or lever 49 is pivotally carried at 50 in a bracket 51 mounted on match ejector lever 18. As match ejector lever 18 is moved forwardly this arm is moved bodily forward, so that one end 49' engages the lower end of arm 46. When, however, the other end 49' of the arm 49 is free, this results merely in rotating arm 49 about its pivot point 50 and arm 46 is not moved. Toe 38, previously referred to, is provided with a second and U-shaped arm 52 which, in the position of Figures 4 and 5, lies in the path of the end 49' of arm 49. With this member 52 in such position motion of lever 18 brings the end 49' in contact with arm 52 and further motion causes the other end 49' to engage arm 46, rotating it about its pivot point and clearing stop 45 from stud 34. Thereupon the associated hopper 3' or 5' will swing from the position of hopper 3' to that of hopper 5', as shown in Figure 1, and the columns of packages therein will be directed into hopper 2 or 4, as the case may be. When the column of cigarettes in the hopper to be replenished has not reached the point shown in column 2 of Figure 1, toe 38 and arm 52 attached thereto will be held in the dotted line position of Figure 5, so that arm 52 is not in position to be engaged by arm 49 when the latter is moved forwardly. Accordingly, no action of the associated hoppers 3' or 5' can take place. When, however, the column of cigarettes is depleted to the point indicated in column 2 of Figure 1, toe 38 is no longer withheld and it and the arm 52 move to the full line position of Figure 5, it being understood that arm 52 is heavier than toe 38 and, hence, is biased by gravity to the full line position. Formed on this member 52, also, is a projection 53 which engages the wall of the unit in the full line position of Figure 5 and prevents rotation past the position of this figure.

As it may be desired to employ column 3 or 5 of the machine in the usual manner, the shelves 37, as has been mentioned previously, are made removable and a catch is provided for each of these columns for the purpose of rendering the shift mechanism inoperative when desired. This catch consists of a rotatable piece 54 pivoted to the rear wall of the unit at 55 and having an arm 56 adapted to pass between toe 38 and the rear wall of the unit to withhold the same in the manner shown in Figure 5. The other arm 57 of this catch is slotted, as shown in Figure 3, to receive a screw driver or the like, and an opening 58 in the rear wall of the unit is provided to furnish access to it (see Figure 1). As is apparent, the catch 54 may be set in the position shown in Figure 3 in solid lines to permit shifting of hopper 3' or 5' or may be rotated counter-clockwise so as to bring arm 56 in front of toe 38 and prevent shifting of either or both of the hoppers 3' and 5' in the manner described.

In the embodiment illustrated, the machine is provided with six hoppers, two of which are adapted to shift container operation. As will be apparent, however, the invention is applicable to machines having different numbers of hoppers without change in any of the features described and in a six-hopper machine can readily be applied to three instead of two of the hoppers, in such case alternate hoppers being adapted to shift operation. As is also apparent, the length of the shiftable hoppers such as 3' and 5' may be varied. In the embodiment shown, hoppers 3' and 5' are adapted to contain about two-thirds of the entire capacity of the hoppers 3 and 5, but it will be readily understood that the capacity of these hoppers could be any desired fraction of the total capacity within reasonably wide limits. Similarly, while the capacity of shift hoppers 3' and 5' is shown as the same, these hoppers can readily be made of different lengths if desired.

A comparison of the embodiment illustrated with a standard six-hopper machine of the prior art reveals immediately the extreme flexibility of the arrangement. Where six brands are stocked the machine of the prior art is adapted to contain the brands only in equal amounts, if the entire capacity is to be utilized. The machine of the present invention, however, can contain six brands also in approximately the following ratios:

The possibility of variation is greatly increased where only five brands are stocked, and is also increased by the adaptation of three, instead of two, columns to shift operation according to the invention.

What is claimed is:

1. In a machine of the class described, and in combination, a plurality of chutes arranged in an aligned series adapted to hold columns of articles to be vended, means for selectively discharging articles from the bottoms of columns so held, means for holding reserve supplies of articles adjacent the upper portions of some of said chutes, but not others of said chutes, and means responsive to depletion of articles in a given chute to a predetermined level to effect transfer of a reserve supply into the adjacent chute.

2. In a machine of the class described, and in combination, a plurality of adjacent chutes adapted to hold columns of articles to be vended, means for selectively discharging articles from the bottoms of columns so held, one of said chutes comprising a movable upper portion adapted to hold a reserve supply of articles, and means for shifting said upper portion over to discharge such reserve supply into an adjacent chute upon depletion of a column therein to a predetermined level.

3. In a machine of the class described, and in combination, a plurality of adjacent chutes adapted to hold columns of articles to be vended, means for selectively discharging articles from the bottoms of columns so held, one of said chutes comprising a movable upper portion adapted to hold a reserve supply of articles, and means for shifting said upper portion over to discharge such reserve supply into an adjacent chute comprising actuating means and control means therefor operable by a column of articles within said adjacent chute upon said column being depleted to a predetermined level.

4. In a machine of the class described, and in combination, a plurality of adjacent chutes adapted to hold columns of articles to be vended, means for selectively discharging articles from the bottoms of columns so held, one of said chutes comprising a movable upper portion adapted to hold a reserve supply of articles, and means for shifting said upper portion over to discharge such reserve supply into an adjacent chute, comprising a controlling member positioned at a predetermined level on said adjacent chute, adapted to extend into said adjacent chute and withheld therefrom by articles within said adjacent chute when a column therein extends above said level.

5. In a machine of the class described, and in combination, a plurality of adjacent chutes adapted to hold columns of articles to be vended, means for holding a reserve supply of articles comprising a movable upper portion of one of said chutes, and means for shifting said upper portion over to discharge such reserve supply into an adjacent chute, comprising a controlling member, positioned at a predetermined level on said adjacent chute, adapted to extend into said chute and withheld therefrom by articles within said chute when the column in said chute extends above said level, and an actuating member operable by said discharging means in discharging an article from said last mentioned chute and controlled by said controlling member.

6. In a machine of the class described, and in combination, a plurality of adjacent chutes adapted to hold columns of articles to be vended, means for selectively discharging articles from the bottoms of columns so held, means for holding a reserve supply of articles in the upper portion of one of said chutes and for transferring said reserve supply into an adjacent chute upon depletion of the column therein to a predetermined level, and means for rendering said transferring means inoperative and directing said reserve supply into the lower portion of the chute within which it is held.
